UNITED STATES PATENT OFFICE.

JOSEPH L. HELLYER, OF ICONIUM, IOWA, ASSIGNOR OF ONE-HALF TO
JOHN C. COOK, OF RUSSELL, IOWA.

ORE SEPARATING AND CONCENTRATING MACHINE.

No. 824,927.

Specification of Letters Patent.

Patented July 3, 1906.

Application filed December 4, 1905. Serial No. 290,073.

To all whom it may concern:

Be it known that I, JOSEPH L. HELLYER, a citizen of the United States, residing at Ico-
niuum, in the county of Appanoose and State
of Iowa, have invented new and useful Im-
provements in Ore Separating and Concen-
trating Machines, of which the following is a
specification.

My invention relates to improvements in
ore separating and concentrating machines;
and the invention belongs to that type or
class of machines in which the crushed or re-
duced ore is first dried by means of an in-
clined revolving iron drum, then classified
into various sizes by means of screens, and,
finally, the valuable particles are concen-
trated into as small a bulk as is economically
advantageous by the fall of the particles in
air-currents. This concentration of parti-
cles is generally brought about by the fall of
the particles in water; but, as is well known,
by this process the concentration depends
upon the difference in specific gravity of the
valuable ore and the waste vein stone or
rock. Particles which have equal velocities
of fall, though differing in size and specific
gravity, are said to be "equal falling" or
"equivalent." Consequently before we can
separate properly by water it is necessary to
classify the particles by size, so that equiva-
lence shall not prevent a separation or lessen
its sharpness.

The principal machine for separating par-
ticles of sizes ranging between one inch and
one-fiftieth of an inch is the jig or jigger.
The smaller sizes are separated by a variety
of machines. The action of many of them
is based upon the behavior of particles car-
ried down an inclined plane by a thin stream
of water. If the gradient of the plane and
the strength of the thin current are properly
arranged, the denser particles will be depos-
ited and the specifically lighter ones washed
away, although they may be equal falling if
allowed to settle in deep water.

The paramount object of this invention is
to overcome many of the difficulties exper-
ienced in concentrating in water and to pro-
duce a generally-improved ore separating
and concentrating machine which will be
simple in construction, cheap of manufac-
ture, and efficient in use.

With these ends in view the invention con-
sists in the novel construction, arrangement,

and combination of parts hereinafter de- 55
scribed, illustrated in the accompanying
drawings, and particularly pointed out in the
appended claims.

Referring to the accompanying drawings,
Figure 1 is a longitudinal sectional view of 60
an ore separating and concentrating machine
constructed in accordance with my inven-
tion; Fig. 2, an open end view of the rear or
feed end of the machine; Fig. 3, a perspective
view of several of the cells of the drier-drum 65
shown in relative position.

Similar numerals of reference designate
like parts throughout all the figures of the
drawings.

As shown by the accompanying drawings, 70
the improved ore separating and concen-
trating machine consists of base-beams 1,
supporting the side and end walls 2 of the
machine, and said side and end walls 2 form
the primary and secondary ore-treating 75
trunks 3 and 4, respectively, and at the front
the housing 5, containing the drier grades
and hoppers used for preparing and feeding
the material to said ore-treating trunks.
The primary or first grade ore-treating trunk 80
3 contains a shaker-riddle 6, disposed hori-
zontally by means of arms 7, suitably jour-
naled therein, and said trunks 3 and 4 pro-
vide a vertically-arranged intake suction-
passage 8 at the front and a vertically-ar- 85
ranged suction discharge-passage 9 at the
rear thereof.

The vertically-arranged intake suction-
passages 8 each contain a hingedly-mounted
depending valve-board 9', provided at its 90
lower or free end with a horizontally-ar-
ranged adjusting-bolt 10, by means of which
the volume and force of the air passing up-
wardly through these passages may be con-
trolled and regulated to provide for various 95
ores and the desired concentrations thereof.

The vertically-arranged discharge-passages
9 are each provided with a transversely- 100
mounted dividing board or partition 11, sub-
dividing the discharge-passages into front 100
and rear passages, the front passages dis-
charging the waste ore or tailings, and the
rear passages leading to the suction-fans 12,
carrying in minute quantities the lighter and
finer grades of ore, such as gold-dust, &c., and
other material, such as waste dirt, dust, &c.
In order to catch and save the gold-dust, and
thus prevent the same from being discharged

with the waste dirt, dust, &c., pans 13, containing quicksilver, are slidably mounted within the suction-fan casings 14 at suitable places about the suction-fans 12, as shown, 5 and the waste ore or material is discharged through the discharge-passages 15.

The fine ore which falls through the shaker-riddle 6 falls upon the inclined board 16 and is then conveyed through a downwardly-extending pipe 17 into the vertically-arranged intake suction-passage 8 of the secondary ore-treating trunk 4. Such portion of the ore as is not carried upwardly through the intake suction-passage 8 and through the secondary ore-treating trunk 4 falls beneath the intake end of said suction-passage 8.

The shaker-riddle 6 is operated by means of a pair of arms 18, pivotally secured at one end to the riddle 6 and at the other to a crank-arm 19 of a crank-shaft 20, mounted in suitable bearings 21, intermediate the primary trunk 3 and the housing 5 at the front of the machine.

The ore-drier comprises a cylindrical main body portion 22, suitably mounted in the base portion of the housing 5 and contains a revoluble screw conveyer 23 and is provided at one end with a hopper 24, adapted to receive the ore as received from the crusher. 25 In order to provide for the drying of the ore as the same is conveyed along the inner cylindrical wall 25 of the drier, a series of steam-cells 26 are mounted and interposed between the outer and inner walls 22 and 25, respectively. The cells 26 are supplied with steam by means of an intake-pipe 27 and a discharge-pipe 28, supplied with suitable globe-valves 29, and the steam is permitted to circulate through and about the cells 26 to 30 maintain a uniform heat about the ore as conveyed through and along the walls of the cylinder to the discharge end 30 of the drier.

As the ore is discharged from the drier it is caught and carried up by means of an elevator 31, the discharge end 32 of which conveys the material into a hopper 33, which feeds the ore upon an inclined grader or screen 34, mounted beneath coil-springs 35, suspended upon arms 36, secured to the walls of 40 the housing 5. The grader or screen 34 is sloped or inclined toward the sides, forming an apex at the center beneath the discharge portion of the hopper 33 above, as shown most clearly in Fig. 2 of the drawings, and the sides are formed with troughs 35^a, adapted to receive the coarser ore from the screen and through the medium of the chutes 36^a and other suitable and convenient means convey it back to the crusher. 50

60 The grader or screen 34 is operated by means of an arm 37, pivotally secured at one end to the screen and at the other end secured to a crank-arm 38 of the crank-shaft 20, hereinbefore referred to. Such portion of the ore as passes through the screen 34 falls

upon the chute 39 and is conveyed thereon through the discharge end 40 thereof, which intersects the vertically-arranged intake suction-passage 8 of the primary ore-treating trunk 3, hereinbefore referred to.

The machine is operated by means of any suitable source of power connected by means of a belting 41, passing over a pulley 42, secured to the shaft of the suction-fan 12 of the primary trunk 3, and a second pulley 43 on 70 the same shaft transmits power to a second suction-fan 12 by means of a belting 44, passing over the same and over a pulley 45, secured to the shaft of said second suction-fan. A second pulley 46 on said last-mentioned 80 shaft transmits power by means of a belting 47, extending over a pulley 48, secured to the crank-shaft 20, before referred to. A second pulley 49 transmits power to a pulley 50, mounted on the shaft of the revoluble screw 85 conveyer 23 by means of a belting 51. A pulley 52 on the crank-shaft 20 transmits power to the elevator - pulley 53 above by means of a belting 54, whereby the elevator is operated to elevate the material as received 90 from the discharge end of the drier. Bank-valves 55 are secured at or near the ends of the front passages of the discharge-passages 9, so as to allow tailings of ore to pass out as accumulated therein, and at the same time 95 preventing air-inlet passages at these points.

From the foregoing description, taken in connection with the accompanying drawings, the operation and advantages of my invention will be readily understood.

Having thus described my invention without having attempted to set forth all the forms in which it may be made or all the modes of its use, I declare that what I claim as my invention, and desire to secure by Let- 100 ters Patent, is—

1. An ore separating and concentrating machine, consisting of primary and secondary ore-treating trunks, a vertically-arranged intake suction-passage formed at the front of said trunks, a vertically-arranged suction discharge-passage at the rear thereof, depending valve-boards hingedly mounted in said intake suction-passages, suction-fans mounted at the ends of said suction discharge-passages, a housing formed at the front and provided at its top with a hopper, a grader or screen mounted beneath said hopper, a chute mounted beneath said screen and adapted to convey material to the intake suction-passage of said primary ore-treating trunk, an ore-drier mounted beneath said chute, and an elevator adapted to convey the material from said ore-drier to said hopper.

2. An ore separating and concentrating machine, consisting of horizontally-arranged primary and secondary ore-treating trunks, vertically-arranged intake and discharge suction-passages formed at the front and rear portions thereof respectively, depending 120

valves mounted in said intake suction-passages, and suction-fans mounted at the ends of said discharge suction-passages.

3. An ore-separating machine, consisting of primary and secondary ore-treating trunks provided with vertically-arranged intake and discharge suction-passages and suction-fans mounted therein, depending valve-boards mounted in said intake-passages, a hopper mounted at the front portion of the machine, a grader or screen mounted beneath said hopper, a chute mounted beneath said screen and adapted to convey the material to said primary ore-treating trunk, and a drier adapted to receive the material and dry the same for deposit in said hopper.

4. In an ore-separating machine, the combination with means for drying and sizing the ore, and a primary ore-treating trunk adapted to receive the ore from the drying and sizing mechanism and containing a shaker-riddle; of a secondary ore-treating trunk mounted beneath said primary trunk, a connecting-pipe mounted between said primary trunk and the receiving portion of said secondary trunk, depending valve-boards mounted in the receiving portions of said trunks, suction-fans mounted in the discharge portions of said trunks, and means for operating said shaker-riddle and said drying and sizing mechanism.

5. In an ore separating and concentrating machine, the combination with a primary ore-treating trunk provided with vertically-arranged intake and discharge suction-passages and a shaker-riddle mounted therein; of a second ore-treating trunk mounted beneath said first-mentioned trunk, a downwardly-extending pipe connecting said trunks, a dividing-board mounted in said discharge-passages, and depending valves mounted in said intake suction-passages.

6. In an ore-separating and concentrating machine, the combination with ore-treating trunks provided with vertically-arranged intake and discharge passages, valves and suction-fans mounted in said intake and discharge passages, respectively, and a shaker-riddle mounted in one of said trunks; of a hopper and grader mounted in front of said trunks, a chute mounted beneath said grader, and means for operating said grader and shaker-riddle.

7. In an ore separating and concentrating machine, the combination with an ore-treating trunk horizontally-arranged and provided with a vertically-arranged intake-passage; of a vertically-arranged discharge suction-passage, a transversely-mounted dividing board or partition mounted therein, and a suction-fan and bank-valve mounted at the end of said discharge suction-passage.

8. In an ore separating and concentrating machine, the combination with a primary

ore-treating trunk provided with a vertically-arranged intake suction-passage, a depending valve mounted in said intake suction-passage, and a shaker-riddle mounted in said primary ore-treating trunk; of a vertically-arranged discharge suction-passage, a suction-fan mounted at the lower end of said discharge suction-passage, and a dividing-board mounted in said discharge suction-passage to form front and rear passages one of the passages being adapted to discharge the waste ore or tailings and the other leading directly to the suction-fan.

9. In an ore separating and concentrating machine, the combination with a horizontally-arranged ore-treating trunk provided with a vertically-arranged intake suction-passage having a depending valve; of a vertically-arranged shaker-riddle mounted in said trunk, a vertically-arranged suction discharge-passage, a dividing-board mounted therein and providing front and rear passages, one of the passages leading directly to the suction-fan and the other being provided with a bank-valve.

10. In an ore separating and concentrating machine, the combination with a horizontally-arranged ore-treating trunk provided with a vertically-arranged discharge suction-passage having a suction-fan at its lower end; and a vertically-arranged discharge-passage provided with a bank-valve, of a pan, containing quicksilver, mounted within the suction-fan casing and adapted to catch the gold-dust as discharged from the discharge suction-passage.

11. An ore separating and concentrating machine, consisting of primary and secondary ore-treating trunks and provided with intake suction-passages, a vertically-arranged suction discharge-passage at the rear thereof, valve-boards in said intake suction-passages, suction-fans mounted at the end of said suction discharge-passages, and a dividing-board or partition mounted in said discharge suction-passages to form front and rear passages, one of the passages being adapted to discharge the waste ore or tailings and the other leading directly to the suction-fans.

12. In an ore separating and concentrating machine, the combination with primary and secondary ore-treating trunks provided with vertically-arranged discharge-passages, and a shaker-riddle mounted in said primary ore-treating trunk; of dividing-boards mounted in said discharge-passages and forming front and rear passages therein, and suction-fans and bank-valves mounted at the lower ends of said front and rear passages, respectively.

13. In an ore separating and concentrating machine, the combination with an ore-treating trunk provided with discharge-passages, and a bank-valve mounted at the lower end of one of said discharge-passages; of a suc-

tion-fan mounted at the end of the other discharge-passage, and a pan containing quicksilver mounted therein adjacent to said suction-fan.

5 14. In an ore separating and concentrating machine, the combination with a horizontally-arranged ore-treating trunk containing a shaker-riddle and provided with a discharge-passage having a bank-valve; of a suction-

passage provided with a suction-fan and a pan, containing quicksilver.

In testimony whereof I have affixed my signature in presence of two subscribing witnesses.
